UNITED STATES PATENT OFFICE.

PEISECH BLUM, OF NEW YORK, N. Y.

HAND PIPE CUTTER, THREADER, AND WRENCH.

No. 890,327.

Specification of Letters Patent.

Patented June 9, 1908.

Application filed September 20, 1907. Serial No. 393,852.

To all whom it may concern:

Be it known that I, PEISECH BLUM, a citizen of the United States, residing at 1697 Lexington avenue, New York, county of New

5 York, and State of New York, have invented certain new and useful Improvements in Hand Pipe Cutters, Threaders, and Wrenches, fully described and represented in the following specification and the accompanying drawings, forming a part of the same.

10 The object of this invention is to furnish a pipe fitter's or gas fitter's hand-tool with a pipe-cutter and with a pipe-threading die, so that the same tool may be used to cut off 15 lengths of pipe and to form threads upon their ends.

The tool is of the class having two hand-levers jointed together, and the cutter in the present invention is journaled in the end of 20 an arm which is pivoted upon one of the levers, and is connected by a link to the other lever so that the pressing of the levers together forces the cutter toward the pivot of the levers. One of the levers is termed here- 25 in the "main lever", upon which the "actuating lever" and the "cutter-arm" are pivoted at a suitable distance apart, and the actuating lever is provided with a jaw or seat upon which the pipe is supported during the 30 operation of the cutter. Rolls are journaled upon the actuating lever in suitable positions to support pipes of different diameters when the cutter is in operation.

A die-holder is provided for the threading- 35 die, having guides for the die to hold the same between the two hand-levers, the holder having lugs to embrace the outer side of the levers to hold them closed, and the holder having buttons or other means of 40 locking the holder upon the levers, when the die and holder are in use. The threading die-holder is secured in a fixed position upon the levers by a pin in the holder engaging a hole in one of the levers. The cutter-arm is 45 so pivoted that the cutter crowds normally into the pipe when rotated around the same for cutting it off.

The invention will be understood by reference to the annexed drawing, in which

50 Figure 1 is a side elevation of the tool with the levers closed and the threading die-holder clamped thereon; Fig. 2 is a plan of the threading die-holder; Fig. 3 shows the inner side of the same opposite to that shown in Fig. 1; Fig. 4 is an edge view of the threading die-holder; Fig. 5 is a front view of the

die detached from the holder; and Fig. 6 is a side view of the pipe-bushing detached from the holder. Fig. 7 is a side view of the tool with the threading die-holder removed and 60 the levers separated to operate upon a relatively large pipe; Fig. 8 is an edge view of the tool which is represented with the levers separated, as in Fig. 7, but the holder shown at the side of one of the levers as it would 65 appear when in its operative connection therewith.

a designates the main lever having a pivot b for the actuating lever c. The main lever is extended beyond the pivot b, with a lateral 70 curve d', to a pivot d upon which the cutter-arm e is jointed and carries the cutter f journaled upon its end. The actuating lever c has an extension c', the free end of which is provided with a pipe bearing roll e'. The 75 pivots g' of this roll and of the cutter f are coupled by links g. Adjacent to the pivot b, the actuating lever is provided with a jaw i which is curved upwardly toward the cutter, and serves as a seat to support the pipe 80 o or o' during the cutting operation. A groove f' is formed in the jaw to admit and clear the "bur" which forms upon the exterior of the pipe when penetrated by the cutter. 85

A roll n is journaled upon the jaw adjacent to the pivot b, and operates to sustain small pipes like the pipe o shown in Fig. 1, during the cutting operation, while the roll h operates to sustain larger pipes, like the pipe o' 90 shown in Fig. 7.

The main lever a is provided beyond the pivot d with a pipe wrench jaw j, and the cutter-arm e is provided beyond the same pivot with a similar opposed wrench jaw k. 95

The movement of the levers or handles a, c, operates to open and close these wrench jaws, as well as to move the cutter f to and from the seat or jaw i, and the levers thus serve a double function. 100

To facilitate the manufacture, the main arm a is formed with a recess a' in one side extending past the pivots b and d, to receiving the actuating arm c; and to centralize all the strains upon the cutter and pipe supporting rolls, the cutter-arm is forked, as shown in Fig. 8, and the pivot extended through the cutter has the links secured upon both its opposite ends. In like manner, the free end or extension c' of the actuating arm 105 is forked to carry the roll e', and the pivot of such roll is in like manner extended beyond 110

the sides of such end to receive the links *g*. The ears upon the base of the jaw *i* which carry the roll *n* also from a fork to receive the roll, so that the rolls and cutter lie upon the center line of the levers.

5 To support the pivots *b* and *d* upon the outer side of the recess *a'*, a re-inforcing plate *z* is applied to the face of the main lever over the recess, and secured to the lever at both ends by screws or rivets *z'*. The pivots of the levers are thus firmly held at both ends. To further stiffen the lever *a*, a marginal rib or web *a''* is projected from the curved portion *c'* of the main lever, between the pivots *b* and *d* as shown in dotted lines in Fig. 1. The levers also serve a third function, in carrying the threading die-holder which is shown with a plate *l* carrying transfer guides *m*, *m'*, adapted to fit between the levers when closed, 10 as shown in Fig. 1, and such guides being dovetailed, as shown in Fig. 4, to receive pipe-dies *p*. Hooks or lugs *q* are formed upon the holder-plate to embrace the outer edges of the levers, and a pin *r* is provided upon the holder to fit a hole *s* in one of the levers. Buttons *t*, *t'*, are shown pivoted upon the guides *m*, *m'*, and adapted to lock over the faces of the levers *a*, *c*.

15 A socket *u* is shown in the plate *l* of the die-holder, and the pipe-guide bushing *v* is shown formed with a hub *v'* upon the forward end which fits this socket. The bushing is also formed with a flange *w* to fit the outer side of the plate *l*, which flange has notches *x* which pass over the heads *y* of studs *y'* set in the plate adjacent to the socket *u*. The heads of the studs serve to lock the holder to the plate by engagement with the edges of the notches *x*, as is shown 20 in Fig. 1.

25 The dies being removable from the guides *m*, *m'*, may be made with any sized cutting aperture to thread pipes of different sizes within the range of the tool; and the bushings *v* are similarly made interchangeable with the socket *u* and perforated to fit pipes of different sizes. A single tool is thus provided with convenient means for cutting off the pipe, for threading the same, and for 30 screwing the pipe into fittings by means of the wrench jaws *j* and *k*.

Having thus set forth the nature of the invention what is claimed herein is:

35 1. A pipe fitter's tool having two hand-levers jointed together, a cutter-arm pivoted upon one of the levers, and the other lever having a jaw to support the pipe to be cut and having a link connected with the cutter-arm, the whereby cutter is moved toward the 40 jaw when the hand-levers are pressed together.

45 2. A pipe fitter's tool having two hand-levers jointed together, a cutter-arm pivoted upon one of the levers, and the other lever having a jaw and a roller to support the pipe

50 to be cut, and having a link connected with the cutter-arm for pressing the cutter toward said roller.

55 3. A pipe fitter's tool having two hand-levers jointed together, a cutter-arm pivoted upon one of the levers, and the other lever having a jaw to support the pipe to be cut and having upon its free end a roller to support the pipe and a link extended to the cutter-arm to actuate the cutter.

60 4. A pipe fitter's tool having two hand-levers jointed together, a cutter-arm pivoted upon one of the levers and the other lever having a jaw to support the pipe to be cut and having a link connected with the cutter-arm, and the main-lever and the cutter-arm having extensions beyond their pivoted point of conjunction provided with pipe wrench jaws.

65 5. A pipe fitter's tool having two hand-levers jointed together, a cutter-arm pivoted upon one of the levers and actuated by connection to the other lever, and a threading-die-holder fitted between the lever-arms and engaged therewith by a pin and clamping buttons.

70 6. A pipe fitter's tool having two hand-levers jointed together, a cutter-arm pivoted upon one of the levers and actuated by connection to the other lever, and a threading-die-holder fitted between the lever-arms and provided with means for locking it thereon and having dies fitted detachably thereto, a socket in line with the center of the dies, and a pipe bushing fitted detachably to such 75 socket.

75 7. A pipe fitter's tool having two hand-levers jointed together, a pipe-cutter actuated by the levers, and a threading-die-holder fitted between the levers when closed and provided with lugs to hold the levers closed, and with buttons for securing the holder upon the levers.

80 8. A pipe fitter's tool having two hand-levers jointed together, a pipe-cutter actuated by the levers, and a threading-die-holder fitted between the levers when closed and provided with lugs to hold the levers closed, guides for holding a pipe-die detachably in the holder, a socket in line with the center of the dies, and a pipe bushing having notched flange and hub fitted to said socket and a stud with head secured upon the holder adjacent to the flange, for locking the bushing in place by the rotation of the flange.

85 9. A pipe fitter's tool having a main lever *a* and an actuating lever *c* jointed together, the main lever having two pivots *b* and *d* and the recess *a'* in the side extending between and past the pivots, the actuating lever *c* jointed upon one of the pivots, and the cutter-arm *e* jointed upon the other pivot with a revolute cutter *f* in its end, a connection between the ends of the actuating lever and the cutter-arm, and the reinforcing plate *z* ap-

plied to the main lever over the actuating lever and cutter-arm and embracing the pivots of the two arms and secured to the face of the main lever beyond said pivots.

5 10. A pipe fitter's tool having a main lever *a* and an actuating lever *c* jointed together, the main lever having two pivots *b* and *d*, and the recess *a'* in the side extending between and past the pivots, the actuating lever *c* jointed upon one of the pivots and provided with the jaw *i* and having the roll *e'* inserted in a fork in its free end, the cutter-arm *e* jointed upon the other pivot and forked in

the end with cutter *f* journaled in the fork, pivots *g'* extended through the roll *e'* and 15 the cutter, and links *g* applied to the ends of the pivots, to connect the actuating lever and cutting-arm.

In testimony whereof I have hereunto set my hand in the presence of two subscribing 20 witnesses.

PEISECH BLUM.
